DRIVE AND TRACK ASSEMBLY FOR FLEXIBLE BELT CARRIER

Floyd E. Collette, 713 4th St., Farmington, Minn.

Filed Apr. 7, 1958, Ser. No. 726,838

7 Claims. (Cl. 211—1.5)

This invention relates to flexible endless belt carriers and more particularly to a drive and track assembly therefor.

It is an important object of the present invention to provide a simple and inexpensive endless conveyor which will utilize plain elements in novel cooperation to efficiently perform its function.

Another object of the invention is to provide a track for an edgewise flexible belt carrier which, when utilized with the drive members disclosed herein, will maintain the carrier without side thrust thereagainst for free running along both curves and straight sections.

It is a further object of the invention to provide a belt drive which will be interposed between the circumference of a horizontal wheel and a flexible belt carrier so as to be capable of providing not only the motivating force for the carrier, but also providing anti-slip means to insure positive driving of the carrier.

These and other objects and advantages of the invention will more fully appear from the following description, made in connection with the accompanying drawings, wherein like reference characters refer to the same or similar parts in the several views and in which:

Figure 1 is a perspective view taken from underneath my apparatus, portions of the supports being cut away as unessential to the view;

Figure 2 is a top view of the apparatus;

Figure 3 is an enlarged vertical section taken on the line 3—3 of Figure 2;

Figure 4 is a fragment of the flexible carrier belt showing the means for securing the ends together; and

Figure 5 is an enlarged horizontal section taken on the line 5—5 of Figure 4.

With continued reference to the drawing, my apparatus is shown in its entirety in Fig. 1 and comprises a track 10 secured to supporting framework 11 in rigidly fixed manner. The moving parts of the apparatus comprise the wheel elements 12, the flexible carrier means 13, roller means 14 and the article suspending means 15. The power driving means is shown generally at 16.

The track 10 is made up of tubular sections 17 which are curved in arcuate bends and straight portions 18 which are tangential to the arcuate bends of the curved portion 17. All of the tubular sections of track 10 are provided with bottom slots 19, as shown in Fig. 3, which form a continuous opening for the length of the endless track 10. Individual sections of track 10 may be joined and kept in alignment by sleeve members 20 which, of course, are provided with slots 21 aligned with the tubular slots 19 so as to provide the requisite continuity of the slotted trackway.

The frame 11 comprises supports 22 which are rigidly secured to horizontal brace members 23 which, in turn, extend outwardly and are secured to the sides of the track 10, as shown in Fig. 2. Details of connections between various brace members 23 are shown in Fig. 3. I may conveniently employ a square tube 24 longitudinally of the apparatus, the latter being drilled at inter-

2

vals to receive a tie bolt 25, as shown. Expanding washers 26 are slipped into the ends of the braces 23 before they are fastened at their outer ends to the track 10 and, upon drawing up the tie bolt 25, the braces 23 will be firmly abutted against the square tube 24. The tubular track 10 may be similarly secured to the outer ends of the braces 23 by means of a bolt 27 passing through the expanding washers 28 and through the side wall of tube 10 where a nut 29 is threadedly mounted on the end of bolt 27. An opening 30 may be formed through the tube 10 in opposed relation to each of the bolts 27 and nuts 29 thereon so that the frame assemblage may be completed with an appropriate tool inserted through the opening 30. A wheel 12 is journaled on shaft 31 secured in vertically depending relation from the framework 11 and is adapted to rotate in a horizontal plane parallel to that of the general framework 11. The outer circumference 32 of each of the wheels 12 has a radius of curvature equal to that of its associated arcuate section 17 and underlies the slot 19 in registered relation as shown in Figs. 2 and 3. The rim or outer circumference 32 of each of the wheels 12 is grooved at 33 so as to receive one or more of the V-belts 34 as shown. The V-belts 34 extend inwardly and are trained about a drive pulley 35 which forms a part of the motor assembly 36 mounted on frame 11 to serve as the power drive means 16. The V-belts 34 also lie in a horizontal plane and the drive pulley 35 and its associated motor 36 are positioned within the area defined by the endless track 10 and is so spaced that there is no interference with the operation of the wheels 12 or the endless track 10.

An endless flexible belt 37 is mounted edgewise of track 10 and extends upwardly through the bottom slot 19, as shown in Fig. 3. The belt has its upper margin 38 within the tubular track 10 and is provided with roller means such as the pair of spaced rollers 39 journaled to the belt at spaced intervals along its full endless length. The rollers 39 lie closely parallel to the upper margin 38 of belt 37 and are adapted to ride on the track portions 40 adjacent the slot 19, as shown. Belt 37 depends from the pairs of rollers and hangs vertically through the slot 19 without touching or rubbing the sides thereof during normal usage of the apparatus.

In order to maintain this precise location of the belt 37 at the arcuate bends in track 10, the intermediate band area 41 of belt 37 bears against the V-belts 34 as they ride in the grooves 33 at periphery 32 of wheel 12. Other wheels 12 used at other arcuate bends of track 10 and which may not be utilized for driving purposes merely press outwardly to contact the same intermediate band area 41 to act as idler wheels for maintaining belt 37 in its precise location with respect to the bottom slot 19 as previously described. The lower margin 42 of belt 37 has a series of suspension linkages 45 flexibly interconnected at 44 and each provided with an upstanding connecting member 43 which terminates in a hook 46 passing through an opening 47 formed through the lower margin 42, as shown. The spacing of the openings 47 and the associated connecting members 45 are completely independent of the positioning and spacing of the pairs of rollers 39 at the upper edge of belt 37. The belt 37 is constructed from a long continuous length of flat material such as phosphor-bronze and the ends 48 and 49 thereof are secured together in overlapping relation, as shown in Figs. 4 and 5, with means for maintaining constant tension thereon. Each of the ends 48 and 49 are provided with spaced parallel slots 50 and each is provided with a pair of grooved abutments 51 in longitudinal alignment with respective slots 50. Each pair of abutments 51 may be secured in opposed relation through

belt end 48, as shown in Figs. 4 and 5. When the respective ends 48 and 49 of belt 37 are overlapped in alignment, the abutments 51 which are secured to the belt end 48 will extend through in free sliding clearance with the slots 50 formed in the belt end 49. Conversely, the abutments 51 secured to the belt end 49 will extend through the slots 50 of the belt end 48 and be in free sliding relation therewith. A pair of tension springs 52 are mounted across each of the upper pairs of grooved abutments 51 and, similarly, a pair of tension springs 52 are secured across the lower groove abutment members 51, as shown in Figs. 4 and 5. The belt ends 48 and 49 are thus permitted longitudinal movement within the limits of the sliding movement of abutments 51 within the associated slots 50. The uppermost pairs of abutments 51, as well as their respective springs 52, are so located with respect to the upper margin 38 of flexible belt 37 that they will all lie within the tubular track 10 when the carrier belt 37 is in operating position. The lowermost set of abutments 51 and associated grooves 50 will naturally lie completely outside the tubular track 10, as shown in Fig. 1.

In the use and operation of my conveyor apparatus and with the various components in position shown in Fig. 1, the motor 16 is energized so as to drive the V-belts 34 in either direction of travel. The associated grooved wheel 12 will rotate and, jointly with the V-belts 34, frictionally drive the edgewise flexible belt 37 and maintain it in proper arc at the curved portions 17 of the tubular track 10. The belt 37 thus has no lateral force against the tubular track 10 but merely remains in vertical relation therewith and in clearance with the edges of the bottom slot 19. The roller means 39 similarly have no side thrust against the tubular track 10 but merely exert a vertical reacting force on the track 10 to sustain the endless flexible belt 37 with any load applied thereto. The suspension linkages 43 are hooked and suspended directly from the lower margin 42 of belt 37 so that these members, together with any load applied thereon, will likewise exert only vertical downward force on the belt.

It is significant that all of the lateral force is absorbed by the outward thrust of the wheels 12 which conform to the precise curvature of the arcuate tubular track portions 17. Because the rollers 39 are parallel with the belt 37 and the belt and suspension linkages 43 are substantially in vertical alignment, no lateral force is applied against tubular track 10 nor is any counteracting lateral force required in the straight portions 18 of the tubular track 10.

Since the flexible belt 37 is continuous in nature, no special relationship need be maintained between the suspension linkages 43 and the roller means 39. It is merely necessary that the rollers 39 be placed at frequent enough intervals to insure proper support of the belt 37 and its suspended articles and that the suspension linkages are flexibly interconnected at convenient intervals not inconsistent with the rate of curvature which they must assume when traveling with the belt 37 about a curved portion 17 of track 10.

It may thus be seen that my belt conveyor utilizing the novel drive and track elements is free-running, yet very light and simple in construction. An unusually heavy load may be applied to the suspension linkages despite the light weight of the entire apparatus. For ordinary circulation of suspended garments, I may use electric motors of small frictional horsepowers with good results.

It will, of course, be understood that various changes may be made in the form, details, arrangements and proportions of the parts without departing from the scope of my invention as set forth in the appended claims.

What I claim is:

1. A conveyor apparatus for carrying suspended articles in an endless pathway comprising, a supporting frame, an endless tube secured substantially in a horizontal plane

to the supporting frame and having a longitudinal bottom slot formed continuously for the length of the tube, said tube having a plurality of arcuate bends and interconnecting tangential portions, an endless belt disposed edgewise with its upper margin lying continuously within said slot, roller means secured at spaced intervals along the upper margin of said belt and lying in parallel relation closely thereto and within said tube in rolling contact therewith adjacent said slot, means depending from the lower edge of said belt for suspending articles therefrom, and a plurality of horizontal wheels lying in a plane parallel to and below the plane of said endless tube and journaled in said supporting frame and each having at its circumference a rate of curvature the same as that of an arcuate bend in said tube, each of said wheels bearing circumferentially outward against said belt below the tube whereby to maintain the belt immediately below said slot and without lateral thrust against the tube.

2. A conveyor apparatus for carrying suspended articles in an endless pathway comprising, a supporting frame, an endless tube secured substantially in a horizontal plane to the supporting frame and having a longitudinal bottom slot formed continuously for the length of the tube, said tube having a plurality of arcuate bends and interconnecting tangential portions, an endless belt disposed edgewise with the upper edge lying continuously within said slot, a plurality of spaced pairs of rollers, each pair being mounted on an axis passing through the upper margin of said belt and having a roller at each side thereof, said pairs of rollers all lying within the endless tube and in rolling contact with the inner tube area immediately adjacent each side of said slot with said belt freely depending therethrough, means depending from the lower edge of said belt for suspending articles therefrom, and a plurality of horizontal wheels lying in a plane parallel to and below the plane of said endless tube and journaled in said supporting frame and each having at its circumference a rate of curvature the same as that of an arcuate bend in said tube, each of said wheels bearing circumferentially outward against the belt at the concave side of each arcuate portion whereby to maintain the belt immediately below said slot and without lateral thrust against the tube.

3. A conveyor apparatus carrying suspended articles in an endless pathway comprising, a supporting frame, an endless tube secured substantially in a horizontal plane to the supporting frame and having a longitudinal bottom slot formed continuously for the length of the tube, said tube having a plurality of arcuate bends and interconnecting tangential portions, an endless belt having an upper margin, an intermediate band area and a lower margin, a plurality of spaced pairs of rollers, each pair being mounted on an axis passing through the upper margin of said belt and having a roller at each side thereof, said pairs of rollers all lying within the endless tube and in rolling contact with the inner tube area adjacent the edge side of each slot with said belt freely depending therethrough, means secured along the lower margin of said belt for suspending articles therefrom, and a plurality of horizontal wheels lying in a plane parallel to and below the plane of said endless tube and journaled in said supporting frame and each having at its circumference a rate of curvature the same as that of an arcuate bend in said tube, each of said wheels bearing circumferentially outward against the intermediate band area of the belt at the concave side of each arcuate portion whereby to maintain the belt immediately below said slot and without lateral thrust against the tube.

4. The structure set forth in claim 1, wherein the means for suspending articles from the belt comprising flexibly interconnected suspension linkages secured at spaced intervals along the lower edge portion of said belt independent of the spacing between the roller means.

5. The structure set forth in claim 1, and a drive pulley positioned within the space bounded by said endless tube,

and a flexible drive belt interposed between the first mentioned belt and the circumference of a wheel and trained about said drive pulley whereby to provide anti-slip driving means therefor.

6. The structure set forth in claim 5, wherein the drive belt is an endless V-belt and the circumferential area of said wheel is provided with a groove for receiving the V-belt.

7. A conveyor belt drive comprising, a driving grooved pulley, a driven grooved pulley in spaced relation to the driving pulley, a V-belt trained about both of said pulleys establishing a driving connection therebetween, and a conveyor belt trained about both of said driven pulley

5
and said V-belt and lying substantially in the same plane therewith, said conveyor belt being pulled into frictional engagement with said V-belt for at least a portion of its arcuate portion trained about said driving pulley.
